METHOD AND APPARATUS FOR MINING COAL

Application filed January 26, 1920, Serial No. 552,137. Renewed April 13, 1922.

The present invention relates to certain new and useful improvements in method and apparatus for mining coal, and has for its object the provision of improved means and 5 method of operation for the taking of coal out of mines. The steps herein disclosed are those of undercutting, breaking down, and loading of coal and it will be understood that, both as to method and apparatus, this disclosure is merely illustrative and in no sense 10 restrictive of the invention.

The principal object of this invention is to provide means for handling a mining machine and a loading conveyer for the more 15 convenient undercutting of the coal at the face of an entry and for the loading out of the coal after it has been shot down.

A further object is the provision of a method 20 of operation whereby a mining machine and a loading conveyer, both of well known construction, may be more advantageously used for the extension of mine entries.

The means and method by which I attain 25 these objects are fully set forth in the following specification and illustrated in the accompanying drawings of which

Fig. 1 is a plan view of a shortwall undercutting machine and a loading conveyer assembled in operative relation for the loading 30 of coal by my improved method.

Fig. 2 is a side elevation of the devices illustrated in Fig. 1 showing the supporting frame work by which these devices are held in operative relation for the loading of coal.

Fig. 3 is a cross section taken along the line 3—3 of Fig. 2.

Figs. 4 to 11 inclusive are diagrammatic figures illustrating a complete cycle in the operation constituting my improved method 40 of entry driving.

Like numerals refer to similar parts in the several figures.

In the drawings the letter "A" indicates as 45 an entirely a coal cutting machine of the well known shortwall type, "B" is a loading conveyer, and "C" is a supporting framework by which the cutting machine and conveyer may be held in operative relation for loading coal. The coal cutting machine "A" has a 50 main frame 1 adapted to rest upon and slide

over the floor of the mine. Attached, preferably rigidly, to the main frame 1 is an elongated horizontally projecting cutter arm 2 provided with a cutter chain 3 having renewable cutter bits 4 adapted to engage the coal to cut it. Upon the main frame 1 are mounted two rope winding drums 5 and 6 upon which are windable the feed rope 7 and the guide and handling rope 8 respectively. The main frame 1 also carries the power devices 55 by which the cutter chain 3 and the winding drums 5 and 6 are actuated and controlled, but as these devices are well known in the art and form no part in the present invention, description of them at this time is not thought 60 to be required.

The loading conveyer "B" comprises a conveyer trough having a forward horizontal section 9 adapted to rest upon the mine floor, an inclined middle portion 10, and a rearward horizontal portion 11 adapted to extend to any suitable point of delivery, as, for example, over a mine car 12 positioned upon the mine tracks in the rear of the machine. Positioned in suitable guideways at the sides of 70 the conveyer trough are parallel endless chains 13 between which, at spaced intervals, extend the conveyer flights 14 by which the material is moved longitudinally of the trough. Secured to the underside of the inclined portion 10 of the conveyer is a supporting framework 15 composed of suitable structural steel shapes, and so positioned as to include the center of gravity of the conveyer structure. The framework 15 has substantially horizontal bottom members 16 adapted to rest upon suitable supporting devices, as will hereinafter appear. This supporting framework 15 contains suitable power and controlling devices by which the conveyer is 75 actuated, but as these devices form no part of the present invention, and are well understood in the art, description of them at this time is not thought to be required.

The supporting framework "C" comprises 85 a base plate 17 adapted to rest upon and slide over the floor of the mine. Attached to the base plate 17 are upwardly extending angle bars 18 connected by suitable cross angles 19, 20 and 21 to form a rigid structure adapted 90

to support the mining machine and conveyer. Attached to the angles 19 and 21 are longitudinally extending angle bars 22, 22 which constitute guideways along which the mining machine "A" may slide, and upon which it may rest during part of the operation of the machine. The guide angles 22, 22 are braced together at their rearward end by an angle bar 23 to which is attached an upstanding bracket 24 adapted to engage the end of either the feed or guide rope to draw the machine rearwardly of the guideways in a manner well understood by those skilled in the operation of such machines. At their forward ends the guide angles 22, 22 are braced together by a plate 25 over which the mining machine may be drawn from the mine floor into the guideways. The base plate 17 and cross angle 20 are extended laterally beyond the guideways 22, 22 to support the loading conveyer in operative relation at the side of the mining machine as shown in Figs. 1 and 3. Attached at opposite sides of the framework "C" near its forward end are guide sheaves 26 and 27 while other similar guide sheaves 28 and 29 are attached near the rear end of said framework to guide the feeding and guiding ropes 7 and 8 to apply their draft at the desired points upon the frame.

In the driving of entries by my improved method the supporting framework "C" is positioned upon the floor of the entry between the end of the mine track and the coal face. The conveyer "B" is secured in position upon the framework "C" and the mining machine "A" is positioned upon the floor of the mine with its cutter arm 2 extending towards the coal face adjacent the left hand rib wall of the entry, as illustrated in Fig. 4. The feed rope 7 will then be connected to an anchor jack 30 placed near the face of the coal at the left hand side of the machine and the guide rope 8 similarly attached to an anchor jack 31 positioned near the coal face at the right hand side of the machine. When now the cutter chain is actuated and the ropes 7 and 8 are wound upon their respective drums at suitable rates of winding the cutter arm will be forced into the coal to make the sumping or entering cut. After sumping the feed rope 8 will be passed around the frame of the mining machine and attached to the anchor jack 32 positioned adjacent the coal face at the right hand side of the entry, as shown in Fig. 5, while the guiding rope 7 will be similarly attached to an anchor jack 33 adjacent the left hand rib in the manner well understood by those skilled in the art of mining. The machine may then be fed across the entry to undercut the coal. When the coal has been cut entirely across the face a suitable anchor jack 34 will be positioned adjacent the forward end of the guideways 22, 22 and the handling rope 8 connected thereto, as illustrated in Fig. 6, and the machine drawn to the position shown

in Fig. 7. By connecting the handling rope 8 to the bracket 24 the mining machine may then be drawn rearwardly upon the guide ways 22, 22 to the position indicated in Fig. 8. After the coal has been shot down in the usual manner the handling rope 8 may be passed around the guide sheave 28, 29 and 27 and attached to a suitable anchor jack 35 positioned near the broken down coal, as shown in Fig. 9. The supporting frame "C" together with the mining machine "A" and loading conveyer "B", may then be drawn forwardly to the position indicated in Fig. 10. During this movement of the machine the cutter chain should be actuated so that the bits 4 may engage the broken fragments of coal and draw them onto the loading conveyer and the pit car 12 should be maintained in suitable position under the discharge end of the conveyer to receive the coal. As soon as the machine reaches the position indicated in Fig. 10 the feed rope 7 will be attached to the jack 36, the guide rope 8 attached to the jack 37 and the entire machine drawn towards the left hand side of the entry, gathering the coal as it goes, until it reaches the position indicated in Fig. 11 at the right hand side of the entry, which completes the cycle of operation. The pit car 12 is then removed, the mining machine "A" unloaded from the supporting frame "C" and the frame "C" and conveyer "B" drawn rearwardly a sufficient distance to afford the necessary clearance for handling the mining machine, and the operation repeated as above described.

This is one method of utilizing the apparatus for cutting kerfs and loading out coal. Other ways of manipulating the machine will suggest themselves to those skilled in the art. For example, it would be entirely possible to place the mechanisms in the position shown in Fig. 7, and, by proper manipulation of the haul ropes and anchors, move the entire apparatus forward to sump; laterally for the cross cutting, and then rearwardly for the withdrawing cut. The cutting element A can then be drawn rearwardly on into guides to such position as best fits it to load the conveyor element B, and the broken down coal loaded out, as hereinbefore described.

It will be understood that all uses and methods of operation of which the apparatus is capable in the hands of those skilled in the art, are to be regarded as within the purview of my invention, even though not specifically referred to and described.

While these methods of mining are especially adapted to the driving of entries, it will be apparent that it is also applicable to the recovery of coal in the rooms of a mine without material departure from the operations above described.

It will be seen that the cutting action in the mine face is the resultant of two compo-

nents of movement, one of the components being the bodily movement of the cutter arm in a rectilinear path parallel to the face and determining the direction of progress, and the other component being the movement of the cutter chain relative to the cutter arm. The same action is utilized in dragging out the broken down material.

While I have described this machine and method in connection with coal mining, and that is its intended use, it will be understood that my reference to the mining of coal is not a limitation of the use of the machine to that particular material.

15 What I claim is:

1. In an apparatus for loading coal in mines, the combination of a supporting frame adapted to rest on the floor of the mine, means to move said frame over said floor, an elongated conveyor mounted on said frame and adapted to gather loose material from the floor in advance of and during the movement of said frame and convey it rearwardly, an arm extending longitudinally of and projecting forwardly of said conveyor, an endless traveling chain carried by said arm, and means on said chain to engage broken down coal on the mine floor in advance of said conveyor and deliver it to said conveyor.

20 2. In an apparatus for loading coal in mines, the combination of a supporting frame, means for moving said frame about the mine, an elongated conveyor mounted on said frame and adapted to gather broken down coal from the floor at points in advance of and during the movement of said frame and convey it rearwardly, an arm projecting forwardly of said conveyor and substantially parallel thereto, an endless traveling chain carried by said arm, and means on said chain to engage broken down coal on the mine floor in advance of said conveyor and deliver it to said conveyor.

25 3. In an apparatus for loading coal in mines, the combination of a supporting frame, means to move the frame about the mine, an elongated conveyor mounted on said frame adapted to gather loose material from the floor in advance of and during the movement of said frame and convey it rearwardly, a laterally offset arm projecting forwardly of said conveyor and substantially parallel therewith, an endless traveling chain carried by said arm, and means on said chain to engage broken down coal on the mine floor in advance of said conveyor and deliver it to said conveyor.

4. In an apparatus for mining coal comprising an undercutting machine having a supporting base, a cutter arm projecting horizontally therefrom, a cutter chain adapted to travel around said arm, and means to move said base to cause said chain to form a kerf at the base of the vein preparatory to blasting down the coal above said kerf, a conveyor

adapted to gather the dislodged coal from the mine floor and convey it rearwardly to elevated discharge points, and a supporting frame adapted to support said undercutter and said conveyor in fixed relation to each other and to be moved relative to the coal to cause said cutter chain while traveling in a coal cutting direction to engage said dislodged coal to drag it onto said conveyor.

5. In an apparatus for mining coal, the combination with a supporting frame, of an elongated conveyor carried by said supporting frame and adapted to gather loose material from the mine floor at points in advance thereof and convey it rearwardly to elevated discharged points, a secondary frame adapted to be optionally supported upon said supporting frame or upon the mine floor independently thereof, and devices carried by said secondary frame adapted to engage loose material upon the mine floor and move it onto the conveyor when said secondary frame is supported upon said supporting frame, or to engage the mine wall to cut a kerf therein when said secondary frame is supported upon said mine floor.

6. An apparatus for mining coal, the combination with a supporting frame, of an elongated conveyor carried by said frame and adapted to gather loose material from the floor of the mine at points in advance thereof and convey it rearwardly to elevated discharged points, a secondary frame adapted to be optionally supported upon said supporting frame or upon the mine floor independently thereof, an arm projecting longitudinally from said secondary frame, an endless chain arranged to travel in guideways upon said arm and having projections adapted to engage the loose material upon the floor of the mine and move it onto said conveyor when said secondary frame is supported upon said supporting frame, or to engage the mine wall to cut a kerf therein when said secondary frame is supported upon the mine floor.

7. In an apparatus for mining coal, the combination with a supporting frame, of an elongated conveyor carried by said frame and adapted to gather loose material from the floor of the mine at points in advance thereof and convey it rearwardly to elevated discharged points, a secondary frame adapted to be optionally supported upon said supporting frame or upon the mine floor independently thereof, devices carried by said secondary frame adapted to engage loose material upon the mine floor and move it onto the conveyor when said secondary frame is supported upon said supporting frame, or to engage the mine wall to cut a kerf therein when said secondary frame is supported upon said mine floor, and power devices upon said secondary frame adapted to actuate said con-

veyor and said coal cutting and moving devices as and for the purpose set forth.

8. In an apparatus for mining coal, the combination with an elongated conveyor adapted to gather loose material from the floor of the mine at points in advance thereof and convey it rearwardly to elevated discharged points of a frame adapted to be connected to said conveyor, an arm projecting longitudinally from said frame, coal engaging devices carried by said arm and adapted to engage loose material upon the mine floor to move it onto said conveyor when said frame is connected to said conveyor or to engage the mine wall to cut a kerf therein when said frame is separated from said conveyor, and power devices upon said frame to actuate said coal engaging devices and said conveyor.

9. In an apparatus for mining coal, the combination with an elongated conveyor adapted to gather loose material from the floor of the mine at points in advance thereof and convey it rearwardly to elevated discharged points, of a frame adapted to be connected to said conveyor, devices carried by said frame adapted to engage loose material upon the mine floor and move it onto said conveyor when said frame is connected to said conveyor, or to engage the mine wall to cut a kerf therein when said frame is separated from said conveyor.

10. In an apparatus for mining coal, the combination with an elongated conveyor adapted to gather loose material from the floor of the mine at points in advance thereof and convey it rearwardly to elevated discharged points, of a frame adapted to be connected to said conveyor, devices carried by said frame adapted to engage loose material upon the mine floor and move it onto said conveyor when said frame is connected to said conveyor, or to engage the mine wall to cut a kerf therein when said frame is separated from said conveyor, and power devices upon said frame to actuate said conveyor and said coal cutting and moving devices.

11. In a machine of the class described, the combination of cutting mechanism adapted to form a kerf in a coal face, conveying mechanism cooperating with said kerf forming mechanism and adapted to receive broken down coal and deliver it to any suitable point, and means for holding said mechanisms against relative lateral movement while permitting relative longitudinal adjustment, said cutting mechanism and conveying mechanism being so related that said cutting mechanism, without changing its direction of movement, will gather broken down material in advance of and deliver it to said conveying mechanism.

12. In a machine of the class described, the combination of cutting mechanism adapted to form a kerf in a coal face, conveying mechanism cooperating with said

kerf forming mechanism and adapted to receive broken down coal and deliver it to any suitable point, and means to maintain said mechanisms in a predetermined angular relation and prevent relative lateral movement 70 while permitting relative longitudinal adjustment, said cutting mechanism and conveying mechanism being so related that said cutting mechanism, without changing its direction of movement, will gather broken down material in advance of and deliver it to said conveying mechanism.

13. In a machine of the class described, the combination of cutting mechanism adapted to form a kerf in a coal face, conveying mechanism adapted to receive broken down coal and deliver it to any suitable point, and means for adjusting said kerf forming mechanism longitudinally with respect to said conveying mechanism and maintaining it in fixed adjusted position, said cutting mechanism being so related to said conveying mechanism that, without change in its direction of movement, said cutting mechanism will gather broken down 85 material in advance of and deliver it directly to said conveying mechanism.

14. In a machine of the class described, the combination of conveying mechanism adapted to receive material at the mine floor and discharge it at any suitable point, cutting mechanism adapted to form a kerf in the face of the coal, means for supporting said cutting mechanism at an angle to the receiving end of said conveying mechanism to engage, without changing its direction of movement, dislodged coal in advance of said conveyor and deliver it directly thereto, and means for effecting longitudinal adjustment of said mechanisms relative to each other.

15. In a machine of the class described a cutting tool traveling in an endless path, means for traversing said tool in a coal face transversely to its path of travel for forming a kerf in said face, a conveyor at an 110 extremity of the path of travel of said tool, said means serving to re-traverse said tool along its cutting path after the coal thereabove has been broken down, and means causing said conveyor to move with the tool 115 during its re-traversing movement whereby the broken coal is delivered by said tool to said conveyor.

16. In a machine of the class described a cutter arm, a cutting tool moving longitudinally and rearwardly of said arm, means for traversing said arm in a coal face transversely to the line of movement of said tool for forming a kerf in said face, a conveyor at the rear of said arm, said means serving to 120 re-traverse said cutter arm along its cutting path after the coal thereabove has been broken down, and means causing said conveyor to participate in the re-traversing movement of said arm whereby the broken 125

down coal is delivered by said tool to said conveyor.

17. The new and improved method of taking material from a mine face, which consists in forming a kerf by a cutting action in the mine face, said action being the resultant of two relatively angularly acting components of movement, one of said components determining the direction of progress and acting in a rectilinear path substantially parallel to the face, and the other of said components acting in an outward path relative to the face; breaking the kerfed material; and repeating the described action to drag out the broken material.

18. The new and improved method of taking material from a mine face, which consists in forming a kerf by a cutting action in the mine face, said action being the resultant of two relatively angularly acting components of movement, one of said components determining the direction of progress and acting in a rectilinear path substantially parallel to the face, and the other of said components acting in an outward path relative to the face; breaking the kerfed material; repeating the described action to drag out the broken material to a point of delivery moving constantly in the direction of progress; and continuously receiving the material at this point and transferring it away.

19. The new and improved method of taking material from a mine face, which consists in forming a kerf by a cutting action in the mine face, said action being the resultant of two relatively angularly acting components of movement, one of said components determining the direction of progress and acting in a rectilinear path substantially parallel to the face, and the other of said components acting in an outward path relative to the face; breaking the kerfed material; and repeating the described action in the original direction of progress to drag out the broken material.

20. The new and improved method of taking material from a mine face, which consists in forming a kerf by a cutting action in the mine face, said action being the resultant of two relatively angularly acting components of movement, one of said components determining the direction of progress and acting in a path across the mine face, and the other of said components acting in an outward path relative to the face; breaking the kerfed material; repeating the described action to drag out the broken material to a point of delivery moving constantly across the mine face; and continuously receiving the material at this point and transferring it away.

21. The new and improved method of taking material from a mine face, which consists in forming a kerf by a cutting action in the mine face, said action being the resultant of

two relatively angularly acting components of movement, one of said components determining the direction of progress and acting in a path across the mine face, and the other of said components acting in an outward path relative to the face; breaking the kerfed material; repeating the described action in the original direction of progress to drag out the broken material to a point of delivery moving constantly across the mine face; and continuously receiving the material at this point and transferring it away.

22. In a machine for loading out coal in a mine, a supporting frame, an elongated horizontally extending arm projecting from said frame, an endless chain having a section travelling toward said frame along an edge of said arm, cutter bits on said chain, an elongated conveyor supported on said frame, said conveyor having an active section with its receiving end at the rear of said bar and at the side of the latter along which said chain section travels, said active section of the conveyor moving in a direction away from said arm and having a delivery end elevated above the floor of the mine, and means to move said frame bodily to engage the cutter bits of said chain section in a pile of disrupted coal to drag the coal fragments toward and deliver them in an unobstructed path to the receiving end of said conveyor section, the latter being adapted to pass the coal over its delivery end to a receiving instrumentality for removal from the mine.

23. The combination with a mining machine comprising a frame, a motor on the frame, a horizontal cutter bar projecting from the frame, a cutter chain travelling around the bar and driven by the motor, and motor driven devices on the frame for moving the latter to advance the cutter bar laterally into material to be engaged, of a conveyor in connection with said frame with its active section extending along the advance side of the frame to receive material from the mine floor and convey it away to a point of delivery out of the path of the machine, said conveyor being moved during the material receiving operation with the mining machine in the advancing direction of and by the moving devices of the latter.

24. The combination with a mining machine comprising a frame, a motor on the frame, a horizontal cutter bar projecting from the frame, a cutter chain travelling around the bar and driven by the motor, and motor driven devices on the frame for moving the latter to advance the cutter bar laterally into material to be engaged, of a conveyor connectible with said frame with its active section extending along the advance side of the frame to receive material from the mine floor and convey it away to a point of delivery out of the path of the machine, said conveyor being moved during the material

receiving operation with the mining machine in the advancing direction of and by the moving devices of the latter.

25. The combination with a mining machine comprising a frame, a motor on the frame, a horizontal cutter bar projecting from the frame, a cutter chain travelling around the bar and driven by the motor, and motor driven devices on the frame for moving the latter to advance the cutter bar laterally into material to be engaged, of a conveyor in connection with said frame with its active section extending along the advance side of the frame in substantial continuation of the active section of the cutter chain to receive material from the mine floor and convey it away to a point of delivery out of the path of the machine, said conveyor being moved during the material receiving operation with the mining machine in the advancing direction of and by the moving devices of the latter.

26. The combination with a mining machine comprising a frame, a motor on the frame, a horizontal cutter bar projecting from the frame, a cutter chain travelling around the bar and driven by the motor, and motor driven devices on the frame for moving the latter to advance the cutter bar laterally into material to be engaged, of a conveyor connectible with said frame with its active section extending along the advance side of the frame in substantial continuation of the active section of the cutter chain to receive material from the mine floor and convey it away to a point of delivery out of the path of the machine, said conveyor being moved during the material receiving operation with the mining machine in the advancing direction of and by the moving devices of the latter.

27. The combination with a mining machine comprising a frame, a motor on the frame, a horizontal cutter bar projecting from the frame, a cutter chain travelling around the bar and driven by the motor, and motor driven devices on the frame for moving the latter to advance the cutter bar laterally into material to be engaged, of material engaging devices moving across the advancing face of the frame and adapted to move material across the path of advance of the machine and deliver it outside of said path, said material engaging devices being advanced bodily with the mining machine under the power of the moving devices of the latter.

28. In a machine of the class described, a cutting instrumentality, means for traversing said cutting instrumentality in a coal face, a conveyor associated with said cutting instrumentality, said means serving to re-traverse said cutting instrumentality along its cutting path after the coal thereabove has been broken down, and means causing said conveyor to move with the instrumentality

during its retraversing movement whereby the broken coal is delivered by said instrumentality to said conveyor.

29. In a machine of the class described, a cutting instrumentality, means for traversing said cutting instrumentality in a coal face, a conveyor associated with said cutting instrumentality, said means serving to re-traverse said cutting instrumentality in the same direction along its cutting path after the coal thereabove has been broken down, and means causing said conveyor to move with the instrumentality during its retraversing movement whereby the broken coal is delivered by said instrumentality to said conveyor.

30. The new and improved method of taking material from a mine face, which consists in forming a kerf by a cutting action in the mine face, said action being the resultant of two relatively angularly acting components of movement, one of said components acting in a rectilinear path substantially parallel to the face and one thereof determining the direction of progress of the cutting action; breaking the kerfed material, repeating the described action to remove the broken material to a point of delivery moving constantly in the direction of progress; and continuously receiving the material at this point.

In testimony whereof, I affix my signature.
